(57) **CLAIM**

The ornamental design for an apparatus holder for connection to an apparatus support device, as shown and described.

DESCRIPTION

FIG. 1 is a perspective view of an apparatus holder; FIG. 2 is a right side view of the apparatus holder shown in FIG. 1,

FIG. 3 is a left side view of the apparatus holder shown in FIG. 2,

FIG. 4 is a front view of the apparatus holder shown in FIG. 1,

FIG. 5 is a rear view of the apparatus holder shown in FIG. 1,

FIG. 6 is a top view of the apparatus holder shown in FIG. 1; and,

FIG. 7 is a bottom view of the apparatus holder shown in FIG. 1.

In the apparatus holder for connection to an apparatus support device a snap-in connection is provided for firmly engaging the apparatus holder with the support device. The apparatus holder is adapted to hold an apparatus such as cell phone, a GPS or a tablet.
